UNITED STATES PATENT OFFICE.

JOHN McCAHEY, OF PROVIDENCE, RHODE ISLAND, ASSIGNOR TO THE NEW ENGLAND BUTT COMPANY, OF SAME PLACE.

MACHINE FOR COVERING WIRES OR CABLES.

SPECIFICATION forming part of Letters Patent No. 411,900, dated October 1, 1889.

Application filed June 27, 1889. Serial No. 315,784. (No model.)

To all whom it may concern:

Be it known that I, JOHN McCAHEY, of Providence, in the county of Providence and State of Rhode Island, have invented certain new and useful Improvements in Machines for Covering Wires or Cables; and I do hereby declare that the following is a full, clear, and exact description thereof, reference being had to the accompanying drawings, and to the letters of reference marked thereon, which form a part of this specification.

This invention relates to that class of machines used for covering wires, cables, &c., with a covering of tape, wire, or other material, and is fully illustrated in the accompanying drawings, in which—

Figure 1 shows a front elevation of the machine. Fig. 2 is an elevation of the right side of Fig. 1. Fig. 3 shows a vertical central section lengthwise of one of the tables and the mechanism on it. Fig. 4 is a top view of one of the tables and its mechanism; and Fig. 5 is a top view of one of the guide-tubes, showing the adjustment of the tension of the tape on the tube.

The frame of the machine consists of two upright side frames A A, connected together by horizontal plates called "tables" d d' d² and by two bottom girts D. The top table d supports that part of the machine that draws or feeds the wire or cable b' through the guide-tubes h' while the winding is going on. The tables d² and d' hold the guide-tubes h' and mechanism for winding the covering on the wire or cable as it passes through the guide-tubes.

The tubes and other devices being essentially the same on both tables, a description of one set will answer for both tables.

The winding apparatus proper consists of a circular plate a, having gear-teeth made on its outer periphery and the upper edge of the plate extended out over the teeth to protect them. This plate a has a hub a³ on its under side, which is turned and fitted in a bearing in the table to serve as a support for the plate to rotate on. Another hub a⁴ is put on the top of the plate, and is fitted to receive the guide-tube h', which is made larger at its lower end and recessed out to fit on the end of the top hub. A set-screw a⁵ is tapped into

one side of the recessed portion of the tube h', by which it may be held fast on the hub when set in any position. A central opening is made through the plate and its hubs large enough to allow the largest size of cable intended to be covered to pass through freely; but the tubes h' are made of different sizes and changed according to the size of wire or cable in hand to be covered.

The reel on which the covering material is held while in the machine and its support are shown in Fig. 1, and the construction of the reel in the section shown in Fig. 3.

A knee-plate r is bolted on the face of the plate a and has a vertical slot r^x made in it. The stud a² on which the reel turns has a flat flange on its inner end, by which it is fastened to the knee-plate by a screw-bolt r^o that passes through the stud-flange and the slot in the knee-plate. This arrangement allows the reel to be raised or lowered by sliding the bolt in the slot and to be set at any inclination by turning the stud-flange on the bolt, as the inclination of the reel depends on the width of the covering material and size of wire or cable covered.

The reel that holds the covering material consists of an under plate v', made with a hub having a hole through it to receive the stud a², on which it turns. A similar plate t, with a larger and shorter hub, has a hole through it fitted to slide on the hub of the plate v'. A screw t' is tapped into the upper end of the stud a², and a washer s³, with its outer edge resting on the hub of the plate v', and a spring n² between the screw-head and the washer are arranged so that when the screw t' is screwed in, it will press the plate v' down and cause a friction between the plate and the shoulder of the stud a². Set-screws t^o in the hub of plate t serve to fasten it in any position desired. This construction allows the material to be wound in rolls and put on the reel by removing the plate t without changing the friction upon the reel, or the reel may be taken off of the stud and the material wound directly on it.

The manner of adjusting the tension of the strips in winding them on the wire or cable will be understood from Fig. 5.

When the guide-tube h' is set on the plate-

hub, so that its slot h'' is near the reel, the strip o' will not have far to go on the tube before entering the slot; but by setting the tube so as to carry the slot farther around, the strip 5 will have to go farther around (see dotted lines in Fig. 5) the tube before entering the slot, and it is evident there will be more friction between the tube and the strip, thereby increasing the tension. A collar n' is fitted 10 to slide on the guide-tube h' , and a guide-pin o is inserted diagonally in the collar. A set-screw u'' is tapped in one side of the collar to hold it fast on the tube. By setting this collar n' a little to one side, so that the strip o' 15 will drag over the pin o , a twist and bend can be given to the strip as it leaves the coil or roll, and prevent its edges from being frayed by rubbing against the face of the plates $v' t$, which is necessary when a strip is used having 20 no selvages.

A short horizontal driving-shaft s^2 is held in bearings attached to the frame at each end at the lower front part of the machine, carrying the driving-pulleys b on one end outside 25 of the frame and a small gear-wheel e^2 on its other end. A pair of bevel gear-wheels z , one of which is fast on the shaft s^2 and the other on the upright shaft s' , convey motion by that shaft to the plates a and a' and to the 30 take-up or feed motion at the top of the machine, which is the same, essentially, as that described in my Letters Patent, No. 275,061, dated April 3, 1883. The motion is conveyed from the upright shaft s' to the plates a a' by 35 means of the gear-wheels y y' , that are fast on the shaft. These engage with the gear-wheels c' , which are held on studs movably fastened in slots in the tables d d' . (See Fig. 4.) The gear-wheels c' engage with the 40 gear-wheels e' , and the latter gear-wheels are held on studs secured to the tables at a proper distance from the plates a a' for the teeth of the gears to engage with those of the plates and turn them. The object of holding the 45 gear-wheels c' on studs placed in slots in the tables is to allow those wheels to be set so as to engage with the plates and by taking off the gear-wheels e' to reverse the motion of either one or both of the plates, so that the 50 winding can be done in either direction with both plates or in opposite directions to each other.

The pinion-gear e^2 on the end of the driving-shaft s^2 engages with a larger gear-wheel c^2 , which is held on a stud in the side frame A, 55 Fig. 2, and a pulley l , secured to the wheel c^2 , conveys motion by means of a belt l^2 to a geared reel C, placed in a frame back of the machine to wind up the wire or cable b' as fast as it is delivered by the feed-motion at 60 the top of the machine.

A cup p' is secured on the lower end of the hub a^3 of each plate a by means of a screw-thread on the end of the hub and a similar thread in the opening in the cup to catch the 65 dripping of the oil used to lubricate the bearing and prevent injury to the article being covered if it is rubber or other gum.

A sliding rod r' , held in slips attached to the lower table to shift the driving-belts, is 70 operated by a lever d^3 , attached to the same table.

Having thus described my improvements, what I claim as my invention is—

1. The guide-tube h' , having a longitudinal slot in one side and recessed out at its lower end to fit on the hub of plate a , and provided with a set-screw to hold it in place, in combination with said plate a , a reel attached to said plate, and mechanism to revolve the 80 plate, substantially as and for the purpose specified.

2. The collar n' , furnished with a pin o and set-screw, substantially as described, in combination with the tube h' and plate a , having 85 a reel attached to its face, for the purpose set forth.

3. A reel composed of a plate v' , having a hollow hub on its face, the plate t , provided with a hub having a hole through it fitted to 90 slide on the hub of the plate v' , washer s^3 , spring n^2 , and screw t , in combination with the stud a^2 , knee-plate r , and plate a , substantially as and for the purpose set forth.

4. The combination of plate a , gear-wheel 95 c' , made adjustable to and from said plate by means of a slot made in the table for its stud, substantially as described, with gear-wheels g' and e' , upright shaft s' , and means for rotating said shaft, for the purpose set forth.

JOHN McCACHEY.
